METHOD AND PRODUCT OF SHOE-CONSTRUCTION

Marshall Marasco, University City, Mo.

Application January 31, 1936, Serial No. 61,682

7 Claims. (Cl. 12—142)

This invention relates generally to the manufacture of shoes and more particularly to a method and product of shoe-construction, reference being had to my co-pending application 5 Serial No. 745,874, filed September 28, 1934, of which this present application is a continuation-in-part.

My invention has for its prime object the provision of a method of shoe manufacture, 10 especially for the making of a shoe of the cemented or so-called "compo" type, in which an economy is effected in parts, material, and labor involved in the manufacture of the shoe, and in the provision of a resulting shoe product which, 15 in an unique manner, is highly adapted to snugly and neatly engage and conform itself to the foot of the wearer.

And with the above and other objects in view, my invention resides in the unique method, and 20 in the novel features of form, construction, arrangement, and combination of parts of the resulting product of shoe-manufacture presently described and pointed out in the claims.

In the accompanying drawings (two sheets),— 25 Figure 1 is an inverted perspective view of a shoe-structure embodying my invention, mounted on a last in preparation for the first step of my method of shoe-construction;

Figure 2 is a similar view, representing an intermediate stage of the shoe-construction;

Figure 3 is likewise a similar view, showing the shoe-structure in readiness to receive the sole of the shoe, the latter being shown in inverted perspective in parted relationship to the shoe- 35 structure;

Figure 4 is a sectional view through the instep of the last and its enveloping shoe-structure, the view corresponding approximately to the stage of manufacture shown in Figure 2;

Figure 5 is a similar view, showing a stage of the process succeeding that of the stage of Figure 4;

Figure 6 is a sectional view through the instep of the last and its supported shoe-structure as 45 appearing after the outer sole is applied; and

Figure 7 is a similar sectional view taken through the ball of the last and shoe-structure.

Briefly, my new method of shoe construction consists in providing, in an assembly of shoe material to be made into a finished shoe, and as a part of the other elements of the shoe-structure, a lining having its opposing lower side margins respectively widened or increased in width at the shank, each for extending substantially across 50 and to the opposite side of the shank of the fin-

ished shoe, so that the shank of the shoe is constructed of transversely over-lapping plies of the lining material. Likewise, the upper, (and its doubler, if one is used) has its respective lower side margins widened or increased in width 5 so that the edges of said upper margins abut at the center line, and under the arch, of the finished shoe.

In the usual manner, the lining and the upper are mounted on and pulled over on the last, with 10 a heel-piece temporarily attached to the last, and the customary counter disposed around the heel between the upper and the lining; a suitable adhesive is then applied to and between the respective bottom margins of the lining and the 15 upper, and the two are side-lasted for marginally bounding the ball of, and are also temporarily tacked to, the last, with the lining in non-adherent relation to the last, and the lower edge of the upper in adherent relation to the lower 20 edge of the lining.

Next, the lining and upper at the toe are cemented together, and at the heel also, the lining, counter, and upper are cemented together, and the shoe-material at both the toe and the heel is 25 fitted on the last, temporary holding tacks being applied at the toe, and permanent tacks being applied at the heel, which most conveniently may be done by means of a bed-lasting machine.

Then the widened marginal portion of the re- 30 spective sides of the lining is, by hand or machine and while the shoe-structure is in the grip of the bed-lasting machine, side-lasted along the shank by first stretching one side margin of the lining over the shank of the last in non-adherent relation thereto, then applying a very rapidly drying adhesive to the exposed surface of said margin, and then stretching the other side margin of the 35 lining over the first mentioned margin, such two marginal portions of the lining then becoming 40 quickly firmly adherent one to the other.

As the next step, the upper is side-lasted at both sides of the shoe, so that the edges of the widened lower side margins of the upper abut approximately at the center-line of the shank 45 of the shoe, a suitable adhesive or cement being applied between the exposed surface of the outer overlapping lining margin and the respective upper side margins, which are then temporarily tacked through the lining to the last pending the 50 hardening of the cement or adhesive.

Meanwhile, I have provided an outer sole characterized by having an interior raised face for presenting to the ball of the foot of the wearer of the finished shoe a surface flush with the ad- 55

joining marginal boundaries of the lining and a marginal flange for attachment to the margin of the upper, and, the shank stiffener having been mounted on the shank portion of the shoe-bottom, 5 the temporary tacks are removed and the sole applied, preferably with the aid of a suitable machine, to the shoe material, a suitable adhesive being disposed between the upper and the sole for unifying the same into a strong and sturdy shoe- 10 structure.

Thereafter, the shoe is finished in the usual manner, well known to those skilled in the art and not deemed necessary of further elaboration.

15 Referring now more in detail and by reference characters to the drawings, which illustrate one embodiment of my invention, I provide, as a part of the shoe-structure, a lining A, which in its general contour will, of course, be suitable for the 20 style and size of the shoe to be constructed, but in one particular will, so far as I am aware, depart from the conventional construction in the respect that, in patterning the lining, each side of the lining A is fashioned or cut with an increased width, forming shank lining flaps 1, 1', 25 for extending substantially across and to the opposite side of the shank of the finished shoe.

Likewise, the upper B of the shoe-structure, (and its doubler, if one is used), is patterned with 30 an increased width opposite the shank of the shoe, so that each side of the upper forms an upper-shank flap 2, 2', as it may be said, which will so extend across the shank of the finished shoe that the opposing edge 3, 3', of each upper- 35 shank flap 2, 2', will be in approximate meeting juxtaposition at the center line of the shank.

In the usual manner, the lining A and upper B are mounted on and pulled over the appropriate last C, together with the customary counter 40 D disposed around the heel 4 of the last between the lining A and upper B, the last C, prior to such operation, having had a heel-piece 5 temporarily positioned on the heel 4 of the last, as by a suitable securing member or tack 6.

45 With the shoe-structure so disposed on the last C, it will be seen that the bottom heel-enveloping margin 7 of the lining A, and the similar margin 8 of the upper B, extend substantially beyond the heel 4 of the last C; likewise, the bottom side 50 margin 9 of the lining A, and the bottom side margin 10 of the upper B, extend substantially beyond the ball 11 and toe 12 of the last C; while the lining flaps 1, 1', and upper flaps 2, 2', extend from the shank 13 of the last C, as best 55 seen in Figure 1.

Then, in accordance with my method of shoe-construction, a suitable adhesive or cement 14 is applied to and, it may be especially pointed out, only between, the side margin 9 of the lining A 60 and the side margin 10 of the upper B, and the two are then, preferably by means of a side-lasting machine, side-lasted over the ball 11 of the last and temporarily tacked thereto as by suitable fastening elements or tacks 15, as best seen 65 in Figure 2.

Next, a suitable adhesive is applied between the lining A and upper B at the toe 12 of the shoe, and likewise adhesive material is applied in the proper places at the heel 4 of the shoe, and the 70 last C with the enveloping shoe-structure thereon is preferably now mounted in a bed-lasting machine, which fits the shoe-structure to the last at both the heel and toe thereof, temporary holding tacks 16 being applied at the toe 12, and permanent tacks 17 being applied at the heel 4, of

the last C during the operation of the bed-lasting machine, as will be understood by those skilled in the shoe-making art, and as best seen in Figure 2.

Then, most conveniently while the shoe-structure is in the grip of the bed-lasting machine, the lining flaps 1, 1', are side-lasted over the shank 13 of the last C. This is preferably, though not necessarily, accomplished by hand and is carried out by first drawing one of the flaps, as 1, 10 snugly over and across the shank 13 of the last, so that the free edge of the flap 1 resides substantially at the opposite side of the shank 13.

Still firmly holding the flap 1 in place, a rapidly drying adhesive or cement 18 is applied to 15 the exposed face of the flap 1, and the other flap 1' is quickly drawn in overlapping relationship onto the flap 1, the adhesive 18 being selected of such nature that but a very small interval of time is required for the flaps 1, 1', to become 20 firmly and securely adherent to each other, the shoe-structure at the shank then appearing as best seen in Figure 4.

As the next step, a suitable adhesive, as 19, is applied to the upper flaps 2, 2', and the same are 25 respectively side-lasted over the exposed lining flap 1', so that the respective edges 3, 3', of the flaps 2, 2', meet or substantially abut at the center line of the shank of the shoe, temporarily holding tacks 20 being also applied, as will be 30 understood from Figures 2 and 5.

However, it will be understood that it may sometimes be found desirable to pull the lining and upper-flaps over the shank after the shoe-structure is taken from the bed-lasting machine, 35 and this may be readily done, if such departure from the foregoing procedure will best serve the intended purpose.

After the shoe-structure is removed from the bed-lasting machine, and while the adhesive is 40 drying, the customary shank stiffener 21 is mounted on the shank of the shoe bottom, preferably with the aid of a securing member or nail 22 driven into and clinched within the heel-piece 5; and, as a step preparatory to attaching the 45 out-sole to the shoe, the temporary securing members or tacks 15, 16, and 20, are removed, the shoe-structure then appearing as best seen in Figure 3.

Meanwhile, I have provided an outer sole E 50 for the shoe. The sole E has the usual heel-flap 23 at its heel 24 and is given a bevel skiving 25 along the sides of the heel-portion 24 and shank 26 substantially to a point adjacent the forward end of the shank region, as is customary in the 55 art.

However, the sole E departs from customary practice, so far as I am aware, in that the sole E, around the ball 27 and toe 28 thereof, is skived to form a marginal flange 29 for attachment to 60 the margin 9 of the upper B, the depth of the skiving being substantially equal to the thickness of the cemented margins 9, 10, of the lining A and upper B, respectively, for providing a raised face or integral filler 30 having a height for neatly fitting into the recess 31 which exists between the edges of the margins 9, 10, and the exposed ball portion 11 of the last C, as best seen in Figures 3 and 7.

The sole E is now applied to the shoe-structure 70 with the aid of a suitable adhesive, this work being done preferably by means of a suitable machine, which presses the sole E firmly onto the shoe-structure, the skived margins 25 of the sole neatly engaging the heel margin 8 and instep 75

flaps 2, 2', of the upper B, and so as also to cover and enclose the shank stiffener 21 in a slightly manner, as best seen in Figure 6.

However, at the ball of the shoe, the adhesive is applied merely to the marginal flange 29 of the sole E, for adherence thereof to the margin 18 of the upper B, the raised face 30 of the sole E being pressed firmly into and substantially filling the cavity 31, for presenting to the ball of the foot of the wearer a smooth surface flush with the marginal boundaries 9 of the lining A, as best seen in Figure 7.

The shoe is then finished in the usual manner according to such requirements as may best serve the purpose, which are not here deemed necessary of further description.

Several economies and improvements in the shoe-manufacture are effectuated by employing my described method of shoe manufacture.

In such respect, it may be pointed out that the upper of the shoe is, in the class of shoes here under contemplation, of relatively stretchable material, whereas the lining, or at least that portion of it which extends around the shank and ball of the shoe, is, in my construction, composed of relatively unstretchable material, and this is done so that when, during the later stages of the process, the temporary tacks are removed for subsequently permitting the application of the outer sole of the shoe, the relatively stiff lining, caused to be firmly adherent to the upper by the set of the cement, will so stiffen and reinforce the whole marginal material, which overlaps the sides of the ball of the shoe, as to substantially retain the same in snugly fitting or hugging relationship on and with the last.

In this manner, I avoid the need of an inner sole, which is wholly absent in my improved shoe, and it will be understood, therefore, that no adhesive is applied to the inner face of the lining, the last being wholly naked and bare, except, of course, for the heel-piece 5.

An economy is thus effected by the elimination of the cost of the material required for an inner sole, as well as the cost of performing the extra step of incorporating an inner sole in the shoe.

The resulting shoe construction is possessed of a number of important and unique features and advantages, which promote both the wearability or durability and comfortableness of the shoe to a marked degree.

Thus, by the unique construction of the shank of the shoe, the usual filler is eliminated, its place being taken by the overlapping plies of the lining material, which not only effects an additional economy in the cost of the shoe, but, most importantly, the adherent overlapping plies of the lining stiffen and reinforce the shoe at its instep and provide a smoothly fitting pliable cradle, as it may be said, for snugly and supportingly engaging and readily conforming to the instep of the wearer of the shoe, as will be understood from Figure 6.

Again, a high degree of comfort in the wear of the shoe is effected by the unique construction at the ball of the shoe. As will be seen from Figure 7, the elimination of an inner sole from the shoe and the provision of the filler 30 on the sole E of the shoe present to the ball of the foot of the wearer of the shoe a surface which smoothly merges into the side walls of the upper, so that the upper is thus adapted to neatly and effectively conform itself to, and most comfortably engage and support, the foot of the wearer of the shoe.

Thus, as will be seen, my method of shoe-con-

struction effectuates a substantial economy in the cost of manufacture of the shoe and provides a shoe-product possessed of strong and sturdy characteristics highly conducive to the pleasurable wear of the shoe.

It will be understood that changes and modifications in the particulars of the several steps of manufacture, and in the form, construction, arrangement, and combination of the several parts of the finished shoe may be made and substituted for those herein shown and described without departing from the nature and principle of my invention.

Having thus described my invention, what I claim and desire to secure by Letters Patent is,—

1. Those steps in the manufacture of a shoe which consist in first providing an upper-structure including a lining having its respective lower side margins widened at the shank, then mounting the upper-structure on a last, then laying one margin over the shank of the last in non-adherent relation thereto, and then laying the other margin over the first mentioned margin in adherent relation thereto.

2. Those steps in the manufacture of a shoe which consist in first providing an upper structure including a lining having its respective lower side margins widened at the shank, then mounting the upper-structure on a last, then laying one margin over the shank of the last in non-adherent relation thereto, then applying an adhesive to the exposed surface thereof, and then laying the other margin over the first mentioned margin in adherent relation thereto.

3. In a shoe, a lining having opposed side margins widened at the shank and extending in overlapping relationship substantially from one side to the other of the shank of the shoe, an upper whose opposed lower margins substantially abut centrally of the shank, and an outer sole fixed to the upper and concealing the said abutting margins thereof.

4. In a shoe, a lining having opposed side margins widened at the shank and extending in overlapping relationship substantially from one side to the other of the shank of the shoe, an upper whose opposed lower margins substantially abut centrally of the shank, an outer sole fixed to the upper, and a shank-stiffener disposed intermediate the abutting margins of the upper and said outer sole.

5. The method of making a shoe comprising the steps of providing upper materials including an upper and a lining, said lining having its respective lower side margins widened at the shank, mounting the upper materials on a last, laying one margin over the instep of the last in non-adherent relation thereto, laying the other margin over the first mentioned margin in adherent relation thereto, bringing and securing the lower margins of the upper across the shank portion into flatwise respective abutting relationship, and positioning and securing a shank stiffener longitudinally of the shank in superposed relationship to the line of abutment between the margins of the upper.

6. A shoe comprising an upper and lining fastened into shoe-forming shape, said upper and lining being cemented together and turned inwardly along their lower margins thereby providing a stiffened sole-engaging flange marginally bounding the forepart of the shoe, said flange being laterally widened on both sides of the shoe along the shank portion thereof for extending in overlapping relationship transversely across said

- shank and thereby providing a sole-receiving opening in the forepart of the shoe completely bounded by the margin of said flange, and an outer sole secured to the upper and having its upper surface marginally reduced at the top surface of its forepart thereby providing an upstanding portion shaped to fit within said sole-receiving opening in snug fitting abutment with the margin of the upper flange.
- 5 7. A shoe comprising an upper and lining last-ed into shoe-forming shape, said upper and lining being cemented together and turned inwardly along their lower margins thereby providing a stiffened sole-engaging flange marginally bound-10
15 ing the forepart of the shoe, said flange being laterally widened on both sides of the shoe along

the shank portion thereof for extending in overlapping relationship transversely across said shank and thereby providing a sole-receiving opening in the forepart of the shoe completely bounded by the margin of said flange, and an 5 outer sole secured to the upper and having its upper surface marginally reduced at the top surface of its forepart thereby providing an upstanding portion shaped to fit within said sole-receiving opening in snug fitting abutment with 10 the margin of the upper flange, said upstanding portion along its upwardly presented flat face being flush with the upwardly presented face of the upper flange.

MARSHALL MARASCO. 15
